AIR MATTRESS CONSTRUCTION

Harry O. Veach, Los Angeles, Calif.

Application August 26, 1946, Serial No. 693,053

3 Claims. (Cl. 5—348)

1

This invention pertains to a pneumatic mattress and is particularly directed to a type of mattress which is capable of being used on the ground and on an ordinary bedstead without the necessity of having some external or additional substantially continuous supporting structure beneath the mattress. Generally stated, the present invention relates to a pneumatic bed or mattress having two major portions; a lower portion of relatively rigid form and a top composed of a pliant, impervious sheet material, the top portion being firmly connected to upstanding side walls of the bottom.

It is recognized that heretofore many types of so-called air mattresses, air cushions and the like, have been devised and used. One common form of air mattress comprises a plurality of parallel inflatable tubes of rubberized cloth or other pliant, impervious material, such tubes being nested in parallel relation within an outer bag or covering. Mattresses of this type are not particularly comfortable and can only be used on the ground, the floor or some other flat continuous supporting surface. They cannot be supported on a pair of spaced trestles or by their edges. They cannot, for example, be supported by a normal bed frame because of the bendable or pliant character of the entire mattress.

There are many advantages to an air mattress which are not obtained by the use of springs or ordinary cotton filled mattresses supported upon bed springs. The present invention allows all of the advantages of an air mattress to be obtained without the disadvantages heretofore encountered in normal prior air mattresses.

An object of the present invention, therefore, is to disclose and provide a pneumatic bed or mattress which is sufficiently rigid and self-supporting to permit its use in a normal bed frame or mounted upon trestles or other side or end supports, without detracting from the resiliency and conforming characteristics of an air mattress.

A further object of the invention is to disclose and provide a collapsible mattress or pneumatic bed of novel characteristics.

These and other objects of the invention will become apparent to those skilled in the art from the following detailed disclosures of certain exemplary forms embodying the novel arrangement and construction. For purposes of illustration reference will be had to the appended drawings in which:

Fig. 1 is a perspective view of a pneumatic bed made in accordance with this invention.

2

Fig. 2 is an enlarged transverse section through a portion of the bed shown in Fig. 1.

Fig. 3 is a perspective view partly in section of a modified form of construction.

5 The form of bed shown in Figs. 1 and 2 comprises a bottom portion including a relatively rigid bottom 10 provided with short upstanding side and end walls 11, 12, and the like. The upper edge of the side walls may be provided with an outstanding flange 13. The bottom 10 may be longitudinally ribbed as at 14 in order to impart rigidity to the bottom.

The top portion is composed of a pliant, impervious sheet material generally indicated at 15, 15 such sheet material having downwardly extending sides such as 16. Means are provided for attaching the lower margins of the sides 16 to the upper margins of the side walls 11, 12, etc., of the lower portion 10. Such means may, for example, comprise a metallic rim, sealing or gasket 18 (preferably provided with an upturned inner edge 19) capable of overlying the flange 13 carried between side walls of the lower portion. Both the sealing 18 and the flange 13 are perforated or ported at suitable spaced intervals so as to permit the threaded shafts of bolts 20 to pass therethrough and through the intervening marginal edge of the sides 16 of the top portion so that a firm air-tight seal may be made by the tightening of the wing nuts 21. It will be noted that the top portion is connected to the edges of the flange 11 of the rigid bottom 10 at a point spaced below the plane of the top 15, thereby providing a soft, resilient, edge area to the upper portions of the mattress which soft edge area will not cause injury if a person were to rapidly lower his weight thereon.

It has also been found highly desirable to provide spaced means connecting the top 15 to the bottom 10, thereby creating a tufted effect to the upper surface of the mattress. The inner surface of the bottom 10 may be provided with a plurality of spaced attachment means such as lugs, eyelets, or the like, 24. The inner surface of the top 15 may also be provided with loops 25 cemented, vulcanized or otherwise attached thereto at intervals correlated to the spacing of the lugs 24. The loops 25 and the lugs 24 are then connected as by means of a cord or other pliant, nonelastic, readily bendable connector 26, which limits the upward displacement of the top 15 with respect to the bottom 10.

One of the side walls or end walls, such as 11, is provided with an air inlet valve 27 through 55 which air may be supplied to the chamber formed

by the interconnected bottom portion and the top portion of the mattress.

It will be noted that the entire mattress may be supported by its edges, as, for example, by the bed frame indicated in dash lines at 28, thereby obviating the necessity of supporting the entire bottom surface of the mattress with slats, boards or other paraphernalia.

Fig. 3 shows a modification in which a different form of connection between the top and bottom portions of the mattress is used. Moreover, Fig. 3 illustrates the use of a segmental lower portion to the mattress. The bottom, for example, may be made of telescopic elements such as the elements 30 and 31, each of these elements including a substantially horizontal bottom and upstanding side walls such as the side wall 32. These telescopic portions may be connected together by means of machine screws or bolts and nuts, a suitable gasket being introduced at the joints. Moreover, the side walls 32 need not have a horizontally disposed flange; instead they may be provided with a rib or ribs extending in a plane parallel to the bottom as indicated at 33. The sealing strip may be also in sections and be provided with an indentation or indentations correlated to the ribs 33 so that when the marginal edge of the side 16' of the top 15' is compressed between the sealing strip 34 and the ribbed side walls 32, a tight joint is formed. Suitable wing nuts or other fastening means may be employed for suitably compressing the sealing strip 34 against the edge portions of the top member.

The bed of Fig. 3 is particularly adapted for use by campers or whenever it is desired to have a readily portable pneumatic bed.

It is to be understood that the top element 15 may be made of rubberized cloth or other impregnated or laminated fabric or composition which is pliant, conformable and substantially air-tight or impervious. Various modifications and changes may be made in the arrangement, means whereby an air-tight connection is made between the top element 15 and the substantially rigid bottom portion of the device being provided. The rigid bottom need not be provided with upstanding side walls but may consist of a flat, relatively rigid, ribbed bottom plate, the lower edge of the top element being suitably attached to the margins of such bottom plate.

Variations may also be made in the manner in which the various spaced connectors such as 26 are attached to either the top element, the bottom element, or both. In Fig. 3 the bottom connecting means are shown in the form of a wire 35 provided with spaced loops, the wire being spot-welded to the inner surface of the bottom member 30 while the loops form points of connection with the connectors 26. Various other changes, modifications and adaptations will readily occur to those skilled in the art. All changes and modifications coming within the scope of the appended claims are embraced thereby.

I claim:

1. A pneumatic mattress comprising: a lower portion including a plurality of interlocking rigid

elements, each including a bottom and short upstanding side walls; means for connecting said elements; a top portion composed of a pliant, impervious sheet material having downwardly extending sides; means for connecting the sides of the top portion to the side walls of the interlocking elements at a zone spaced from the plane of the top to form an air-tight seal therebetween, said top portion and lower elements cooperating to form an air-tight chamber and a plurality of spaced, non-elastic but pliant connectors attached to the inner surfaces of the bottoms of the elements and to the pliant top portion to maintain the top in a plane spaced above said bottom and above the upper margins of the short side walls of said bottom.

2. A pneumatic mattress having a self-sustaining bottom capable of being supported by its end portions, comprising: a relatively rigid, self-sustaining bottom; a top portion composed of a pliant, impervious sheet material having downwardly extending sides, means for connecting the lower marginal edges of said downwardly extending, pliant sides to marginal edges of said bottom to form an air-tight seal therebetween, said connecting means being located appreciably below the level of the major portion of said top, said top and bottom portions cooperating to form an air-tight chamber; and inlet means carried by one of said portions for supplying and retaining air in said chamber with the pliant top in spaced relation to the rigid bottom and above marginal edges of such bottom.

3. A pneumatic mattress having a self-sustaining bottom capable of being supported by its end portions, comprising: a relatively rigid, self-sustaining bottom; a top portion composed of a pliant, impervious sheet material having downwardly extending sides, means for connecting the lower marginal edges of said downwardly extending, pliant sides to marginal edges of said bottom to form an air-tight seal therebetween, said connecting means being located appreciably below the level of the major portion of said top, said top and bottom portions cooperating to form an air-tight chamber; inlet means carried by one of said portions for supplying and retaining air in said chamber with the pliant top in spaced relation to the rigid bottom and above marginal edges of such bottom; and a plurality of spaced, non-elastic but pliant connectors attached to the inner surfaces of the bottom and the pliant top.
